AUTOMOBILE SIDE WING BRACKET

James P. Callahan, San Francisco, Calif.

Application August 31, 1931, Serial No. 560,257

8 Claims. (Cl. 296—84)

This invention relates to improvements in the construction of metal brackets used for holding the so-called side wings on automobile doors to shield the occupants from objectionable drafts, 5 and the objects of the invention are to produce a neat inexpensive construction of great effectiveness, as well as adaptability to various shaped door openings.

This application is a continuation in part of 10 my copending application for Side wing bracket filed on August 18, 1930, under Serial No. 475,980 inasmuch as it embraces the underlying principles of construction shown in Figs. 1 and 2 of the drawings of my copending application afore- 15 said, claim to which was ordered divided out of said copending application by the Examiner during the prosecution of the case. The bracket has, however, been additionally improved, as will appear below.

20 In the drawing Fig. 1 is a side elevation of a glass side wing mounted on the door, or rather to the edge of the window opening of the door of an automobile.

Fig. 2 is a cross section of Fig. 1 taken from 25 the line 2—2, with the upper sill removed.

Fig. 3 is an enlarged vertical section of Fig. 1 taken along the line 3—3.

Fig. 4 is a plan view of the lower bracket, as 30 seen from the line 4—4 of Fig. 3.

Fig. 5 is a perspective view of the upper bracket partly disassembled.

Fig. 6 is a broken view showing the sheet metal ball formed on the plates of the upper bracket.

Fig. 7 is a detached perspective view of the 35 outer clamp member of the upper bracket.

Fig. 8 is a detached perspective view of a modified shape of the upper ball clamping plate of the upper bracket.

Fig. 9 is a detached perspective view of the 40 inner clamp member of the upper bracket.

In further detail 1 represents the ordinary automobile door with its window opening 2, outside of which is a plate glass "side wing" 3, held in position by an upper and a lower clamping bracket clamped respectively to the upper and lower edges of the window opening, and which brackets form the subject matter of this application.

The edges of the door window opening are rounded in such a manner that little or no flat 50 space is provided against which to clamp the parts of a bracket, and neither are the openings square or the top and bottom edges parallel, as they follow the car design as indicated by the dotted lines in Fig. 1 showing at 2' the downward slant of the upper edge of the window open-

ing, and it is to meet various conditions in all sizes and shapes of cars that my invention has been developed.

The glass plate 3 is tightly fitted and cemented 5 within grooves of upper and lower bracket plates 4 and 5 in any approved manner, and as the construction of the lower bracket is the simplest, this will first be described.

The lower bracket includes an inner clamp member 6 provided with a straight clamping margin 10 directed at an angle toward the door at its outer edge, and a housing or hollow boss portion 7 covering over the clamping screw 8, as well as the screw engaged lug or boss 9 of the opposed member 10 of the clamp, which fits over and against 15 the rounding edge of the window opening, a piece of sheet rubber 11 being interposed to insure a tight grip, and it will be noted that this rubber extends to the right and is pierced by screw 8 so that when the clamp is disassembled the rubber 20 sheet will not become misplaced.

Outer clamp plate 10 is bent outward at 10' at right angles to the door and vertically pivoted by means of a bolt 12 passing through the members, as well as through a friction plate 13, and if desired, a pair of thin washers as indicated 25 in Fig. 3.

The housing portion 7 of the inner clamp member is closed on its outer end, as best shown at 7' in Fig. 9 where this member is upside down 30 insofar as a description of the lower bracket is concerned. The clamping screw 8 is accessible only from within the automobile so as to make it easy to adjust from within, yet hard to steal from without.

In the action of this device it will be noted 35 that the inner clamping plate is initially slanted to bring its free edge into contact with the door as shown, and as the screw is tightened this plate 6 will tend to straighten, and outer clamp 10 will attempt to crawl upward on the curved edge of the door. However, the glass plate 3 prevents this movement with a result that an extraordinary tight grip is secured on the door edge.

The upper bracket has the counterpart of plate 45 5 in plate 4, which is likewise secured to the glass, but which instead of being pivoted by a small bolt to the clamp members as is lower bracket plate 5, is instead formed with a hollow sheet metal ball 14 formed integrally on plate 5, and which 50 ball is gripped by upper and lower hemispherical sockets 15 and 16 respectively, formed on plates 17 and 18. Plate 18 is formed with a step 18' in it receiving a bent down portion 17' of plate 17 and the two plates are frictionally clamped 55

over the ball 14 by two screws 19, while the lower portion of plate 18 is extended to pass around the rounding outer corner 20 of the window opening and bent downward into an ear or lug 21 to receive a screw 8 corresponding to screw 8 in the lower clamp and operating in a duplicate of the lower clamp member 6, 7, 7' and 8 as described. The strip of rubber 11 is likewise used on the upper clamp.

10 In clamping effect the upper clamp operates just like the lower one described, except that the presence of the ball joint 14 between the plate 4 and the clamping elements 6 and 18 permit these elements to tip with respect to the horizontal or upper edge of the glass as shown in Fig. 1 so that apparatus will accommodate itself to any downward slant of the window opening due to the design of the car body, a feature not properly cared for in prior devices of this kind insofar as I am aware. Through the provision of screws 19, plate 17 may easily be detached and another one of slightly different form substituted so that the precise form to suit the particular car may be supplied. Thus the plate 17 of Fig. 5 is tapered 25 smaller at 17' whereas in Fig. 8 the corresponding clamping portion is shown the same size at both ends as would be used to fit a window opening in which the upper edge is parallel with the lower edge. When odd shaped plates 17 are supplied, 30 they are, of course, furnished right and left for opposite windows of the car. It will be noted that the vertical pivotal axes of the upper and lower brackets are aligned when the apparatus is installed, and that the side wing may be adjusted as desired on this axis.

Having thus described my improved side wing bracket, what I claim is:

1. In an automobile side wing bracket of the character described, a clamp adapted to engage the opposite edges of a door window opening comprising a plate with a margin arranged to bear against the inner side of the door opening and formed with a hollow boss overlying the edge of the opening, and a screw extending into the boss, a second plate bearing curved to fit the rounded outer corner of the window opening and provided with a lug positioned within said hollow boss threadedly engaged by said screw.

2. In an automobile side wing bracket of the character described, a clamp adapted to engage the opposite edges of a door window opening comprising a plate with a margin arranged to bear against the inner side of the door opening and formed with a hollow boss overlying the edge of the opening, and a screw extending into the boss, a second plate bearing curved to fit the rounded outer corner of the window opening and provided with a lug positioned within said hollow boss threadedly engaged by said screw, and a sheet 55 of friction material positioned between said second plate and the window, also extending into said hollow boss and engaged by said screw.

3. In a structure as specified in claim 1, said hollow boss being closed on the outer side and said screw accessible only from inside of the car.

4. In a side wing bracket for automobile door windows, a clamp for the edge of the window opening comprising inner and outer edge clamp-

ing plates, the outer plate formed with a convexed outer wall, the inner plate formed with a hollow boss portion riding on the convexed portion of the outer plate, the outer plate formed with an extension lying within said hollow boss, and a screw extending into the hollow boss engaging said extension for drawing the plates together.

5. An automobile side wing bracket including a clamp adapted to engage the opposite edges of a door window opening comprising a plate with a margin arranged to bear against the inner side of the opening formed with a hollow boss overlying the edge of the opening, a screw extending into the boss, a second plate formed to fit the outer margin of the window opening and provided with a lug positioned within said hollow boss threadedly engaged by said screw, a member arranged and adapted to engage said side wing formed with a ball and said second plate provided with a socket formed to engage said ball for providing a ball and socket connection between the side wing and clamp.

6. In an automobile side wing bracket of the character described, a clamp adapted to engage the opposite edges of a door window opening comprising a plate with a margin arranged to bear against the inner side of the door opening and formed with a hollow boss overlying the edge of the opening, a screw extending into the boss, a second plate arranged and adapted to engage the outer surface of the door adjacent the window opening, said second plate being provided with an extension extending vertically into said hollow boss threadedly engaged by said screw, and a strip of resilient material adapted to be interposed between said second plate and the side of the door.

7. An automobile side wing bracket comprising a clamping member arranged and adapted for clamping to the horizontally extending edge of an automobile window opening and provided with an outwardly projecting portion, a horizontally extending vertically opening channel member adapted to receive within it the horizontal edge of a substantially vertical glass side wing and provided with an inwardly projecting portion overlapping said outwardly projecting portion, and a ball and socket joint connecting said overlapping portions positioned adjacent the edge of the window at a point between the plane of the glass wing and the window edge.

8. An automobile side wing bracket comprising a clamping member arranged and adapted for clamping to the horizontally extending edge of an automobile window opening and provided with an outwardly projecting portion formed with an offset, a horizontally extending vertically opening channel member adapted to receive within it the horizontal edge of a substantially vertical glass side wing and provided with an inwardly projecting portion overlapping said outwardly projecting offset portion, and a ball and socket joint connecting said overlapping portions positioned adjacent the edge of the window at a point between the plane of the glass wing and the window edge.

JAMES P. CALLAHAN.
